UNITED STATES PATENT OFFICE.

JAMES CUMMING, OF BOSTON, MASSACHUSETTS.

TRY-COCK FOR STEAM-BOILERS.

Specification of Letters Patent No. 25,810, dated October 18, 1859.

To all whom it may concern:

Be it known that I, JAMES CUMMING, of Boston, in the county of Suffolk and State of Massachusetts, have invented a new and useful Improvement in Steam-Boiler Try-Cocks; and I do hereby declare that the following is a full, clear, and exact description of the same; reference being had to the accompanying drawings, forming a part of 10 this specification, in which—

Figure 1, is a side elevation of a steam boiler with my improved try-cock applied to it. Fig. 2, is an end view of the same. Fig. 3, is a vertical longitudinal section of the 15 same, and Fig. 4, is a horizontal section.

Similar letters of reference, in each of the several figures indicate corresponding parts.

It has been customary heretofore, to employ a series of try cocks in the end of a 20 boiler, said cocks respectively indicating, by squirting water, the different heights of the water in the boiler and thus enabling a careful engineer to keep the water at a proper or safe level.

25 The nature of my invention consists in the combination, with an ordinary cock of a hollow tube having a turning axis and extending through the end or side of the boiler and at certain periods remaining elevated 30 above the level of the water, but capable of being brought below the same whenever necessary, as hereinafter described.

By my invention, I am not only enabled 35 to accomplish with a single try cock all that is accomplished with a series of try cocks— applied in the ordinary manner—but also to try within the intermediate space generally existing between such series of cocks; for, 40 by simply elevating the outer end of the tube with the hand and opening the try cock, I can ascertain the exact height of water in the boiler, for at the moment the inner end of the tube is brought into the water, or below the level of the same, the water 45 will squirt out through it and the engineer by casting his eye up to the indicator will be informed as to the facts in the case.

To enable others, skilled in the art, to 50 make and use my invention, I will proceed to describe its construction and operation.

A, represents a steam-boiler of ordinary construction.

B, is a metallic plate fastened on the end 55 of the boiler; through this plate an oblong or V shaped opening a, is made, said opening matching an oblong V shaped opening b,

in the boiler. The opening a, enlarges and forms a semi-circular seat c, at the front of the plate, as represented in Figs. 1, 3 and 4. Into the seat c, a cylindrical hollow axis C, 60 is fitted with a ground joint, and through this axis and the opening in the plate and boiler, a hollow tube D, passes, as shown in Fig. 3, said tube being open at the end which enters the boiler and closed with a screw 65 cap d, at its outer end, as shown.

e, is a passage in one side of the tube, this passage matches the bore of the hollow axis, as shown in Fig. 3, by full black lines, and in Fig. 4 by dotted lines. The cap of the 70 tube is pointed so as to serve as a pointer to a dial plate D', arranged in proper relation to it, said plate being marked with words or characters such as are commonly used to indicate high and low or safe and dangerous 75 levels of the water in the boiler.

E, is a try-cock, one end of which is inserted into the bore of the hollow axis, as shown in Figs. 4.

F, is a flat spring for retaining the hollow 80 axis in proper position and thus preventing the tube from falling into the water when no force is applied to the outer end of the tube. This spring is made light enough to allow of the axis and tube being turned with 85 the hand from the position shown in black to the position shown in red, but is sufficiently strong to return and hold the axis and tube in the position shown in black after the height of the water has been ascer- 90 tained.

G, is a flat vane or feeler for indicating 95 to the engineer when the tube first strikes the water. This vane by having a broad surface horizontally will meet with more resistance from the water than the tube would and consequently the engineer will know the moment the tube is about to squirt and thus be enabled to get out of the way of the hot water.

100 From the above description of parts, it will be seen that if it is desired to try the height of water in the boiler, all that has to be done is to open the try cock and apply the hand to the indicating or outer end of the tube and then pull the same down until water begins to squirt out of the cock, as illustrated by arrows in Fig. 4. The water having squirted, the engineer only has to cast his eye to the dial plate and notice the 105 position of the pointer in order to know if the water stands at a safe or dangerous level.

In case the tube becomes clogged or stopped with sediment or from other cause the screw cap at the end of the tube can be removed and a cleansing wire forced through the tube and all obstruction removed.

What I claim as my invention and desire to secure by Letters Patent, is—

The combination with an ordinary try cock E, of a straight hollow tube D, moving vertically on axis C and which is also the indicator at its outer closed end, and extend-

ing through the end or side of the boiler and at certain periods remaining elevated above the level of the water, but capable of being brought below the same, whenever necessary, substantially as and for the purposes set forth.

JAMES CUMMING.
